(57) **CLAIM**

The ornamental design for an oil filter pot, as shown and described.

DESCRIPTION

FIG. 1 is a front, left and top perspective view of an oil filter pot, showing my new design.

FIG. 2 is a rear, right and bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof; and,

FIG. 9 is an exploded perspective view of the oil filter pot of FIG. 1.

The broken lines in the drawings depict portions of the oil filter pot that form no part of the claimed design.
